UNITED STATES PATENT OFFICE.

JAMES E. WEAVER, OF ELIZABETHTOWN, NEW YORK.

ROLLER-SKATE.

1,188,377.

Specification of Letters Patent. Patented June 20, 1916.

Application filed April 22, 1913. Serial No. 762,902.

To all whom it may concern:

Be it known that I, JAMES E. WEAVER, a citizen of the United States, and formerly a resident of Demarest, in the county of Bergen and State of New Jersey, but now a resident of Elizabethtown, in the county of Essex and State of New York, have invented certain new and useful Improvements in Roller-Skates, of which the following is a specification.

My invention relates to roller skates, and has for its object to so construct a skate of this kind that it may be readily convertible from a skate having two pairs of rollers arranged in the customary way, into a skate having two or three rollers arranged in tandem fashion, or into a skate having five rollers, four of them arranged in the usual way, and the fifth centrally between them. Other arrangements of the rollers are also possible with my improved convertible skate.

This skate is adapted for ordinary skating (using the four rollers in that case), or for speed-skating (when a central roller is employed, preferably larger than the other rollers.)

The invention also comprises means for relieving jars, and a brake arrangement which will be particularly useful when coasting.

An example of the numerous ways in which my invention may be carried out will now be described in detail with reference to the accompanying drawings, and the novel features will then be pointed out in the appended claims.

Figure 1 is a side elevation of my improved roller skate, with four rollers in position; Fig. 2 is a bottom view thereof; Fig. 3 is a bottom view with three rollers arranged in tandem fashion; Fig. 4 is a corresponding side elevation; Fig. 5 is a bottom view of the skate with five rollers in position thereon; Figs. 6, 7, and 8 are cross sections on the lines 6—6, 7—7, and 8—8 respectively of Figs. 2 and 4; Fig. 9 is a rear elevation of the skate in the condition illustrated by Figs. 1 and 5; Fig. 10 is a cross section on the line 10—10 of Fig. 5; and Fig. 11 is a partial longitudinal section on line 11—11 of Fig. 2. In several of these views, particularly in the sectional figures, certain parts have been omitted so as to show the structure more clearly.

The body or frame of the improved skate comprises a front plate A and a rear plate

or heel plate B, the latter being provided with any usual or approved projections *a* to which are secured the leather *b* and straps *c* for fastening the skate at the heel, but any other heel-fastening may be employed. The front plate A is shown provided with the usual rivets *d* on which the slotted sole-clamps C are mounted to slide, said clamps having screw-threaded openings through which extends the screw D, held against lengthwise movement by the engagement of its reduced portion *e* with a fork E secured to the front plate A. One end of the screw D is shown angular for the reception of a suitable key (not shown). The sole-clamp arrangement shown is of a well-known character, but any other suitable construction of the clamps may be substituted. The two plates A and B are connected adjustably, so that the skate may be lengthened or shortened. In the construction illustrated, the front plate A is bent down as at *f* so that its rear portion *g* will be at a lower level than the toe portion. The rear plate B is also bent down as at *h*, the forward portion *i* of said plate being adapted to fit below the portion *g* of the front plate A. An opening *j* is provided in the vertical portion *h* of the rear plate, to allow the rear portion or tongue *g* of the front plate A to slide therethrough when the skate is fully shortened, as for convenience in shipping. At its side edges, the forward portion *i* of the rear plate B is formed with upwardly extending flanges *k*, preferably flaring toward their upper edges, on which the forward portion or body of the front plate A is adapted to slide. The downwardly bent portion *f* extends between the flanges *k*, as does also the rear portion or tongue *g*, the latter sliding on the forward portion *i* of the rear plate B. The member or tongue *i* of the rear plate B is slotted lengthwise as at *l* to receive a bolt F secured to the tongue *g* of the front plate A, this bolt having a nut *m* for fastening the plates A and B together in any position to which they may have been adjusted. The flanges *k* with the tongue or forward portion *i* of the rear plate B, form a trough-like structure which stiffens and strengthens the skate materially. The tongue *g* of the forward plate A is also slotted lengthwise, as at *o*, for a purpose stated hereinafter, the two slots *l* and *o* being in registry with each other.

Near the forward end of the front plate

A is secured a bracket G, the vertical end members of which receive a pivot pin H forming a fulcrum for carrying arms J extending rearwardly and supporting an axle 5 K on which the two front rollers L are mounted to turn. The axle is screw-threaded in its entire length, and is held in position on said arms J in the following manner: The arms J are made with approximately circular openings p from which slots q, open at the bottom, extend downwardly. These slots are of sufficient width to allow the axle to be inserted upwardly or withdrawn downwardly. On the inside 10 of the arms J, nuts M are screwed on the axle K, each of said nuts having a cylindrical projection r which fits into the adjacent openings p, and projects therethrough to the outside of the arm J. On the portion 15 of the projection r which is outside the arm J, a washer N is fitted against the outside of the arm, and then comes a curved dust-plate O of well-known character. Externally of this, a cone P is screwed on the 20 axle K, said cone having a race for the balls Q also engaging a race in the roller L. A similar race at the outer portion of the roller engages balls R in contact with a cone S screwing on the axle K. Then follows another dust-plate T, a small washer U, and a nut V screwed on the axle K.

The parts M, N, U, and V have been omitted from Fig. 4 in order to show more clearly, the opening p and the slot q provided in the arm J.

The carrying arms J are formed integral with a cross piece s to which is secured a bar W projecting outwardly over the in-turned flanges t of a U-shaped plate X secured to the front plate A. Between the bar W and the plate X is placed a cushion u of rubber or other suitable elastic material. Thus the arms carrying the front rollers L are capable of a slight up and down movement on the pivot H, the cushion u relieving jars.

A somewhat similar construction is employed for supporting the rear rollers L'. They are mounted to turn on an axle K' 50 screw-threaded in its entire length and carrying nuts, cones, washers, etc., in the same manner as described with reference to the front axle K, as will be understood from the use of corresponding reference letters. 55 The arms J' carrying the rear axle K' are pivoted at H' on a bracket G' secured rigidly to the rear plate B. The pivot H' is located at the forward end of the arms J'. To the cross member s connecting the rear ends 60 of the arms J' is secured a bar W' the ends of which project over the in-turned flanges t' of a U-shaped plate X' secured to the rear plate B. The cushioning effect is obtained in this case by means of a spring Y 65 having its forward end secured to the rear

plate B, for instance by means of the same rivets which fasten the bracket G'. The rear end of the spring Y rests on top of the bar W' and tends to force it against the flanges t'. A cam lever Z is pivoted to the rear plate B at r to swing about a vertical axis located forward of the plate X'. The rear end of this lever extends between said plate X' and the spring Y is provided with a handle w within easy reach of the person 70 using the skate. The lever Z can thus swing from side to side between the vertical members of the plate X'. In one position, the lever Z clears the spring Y and allows the bar W' and arms J' to move upward relatively to the plate B (or rather, the plate B to move downward in relation to the rear ends of the arms J'), thereby bringing the rear rollers L' in contact with brake shoes x (of wood, leather, or other suitable material) carried by the plate X'. In its other position, the lever Z engages the spring Y and locks the arms J' to the rear plate B by pressing the bar W' firmly against the flanges t', so that the brake shoes x cannot 80 engage the rollers L'. Preferably the lever Z is self-locking in either of its positions, which may be accomplished by making the lever elastic, with a tendency to spring upward into one or the other of two locking 85 notches y provided in the plate X'. 90

In order to prevent the inner nuts M, M' from getting loose or "backing off", a holding sleeve z may be put on the axle K or K' after these nuts have been screwed tight. 100 This sleeve is split and made of elastic metal so that it can be sprung over the axle to apply the sleeve, or to remove it for the purpose of converting the skate in the manner set forth hereinafter.

The rear portion g of the front plate A is adapted to slide rearward under the forward end of the spring Y and above the pivot H', between the vertical members of the bracket G'. 105

So far as described above, the skate is a roller skate having four rollers, a front pair and a rear pair. In ordinary use, the lever Z will stand so as to engage the spring Y and lock the arms J' to the rear plate, thus putting the brakes x out of action. When coasting, the lever Z is preferably in the other position, that is to say, it will be swung clear of the spring Y, the latter will still normally keep the brake shoes x 110 out of engagement with the rollers L', but when the user desires to bring the brakes into action, he can do so by simply putting his weight on his heel, thus causing the arms J' to swing on their pivot H' and 115 bringing the brake shoes x against the rear rollers L'. Coasting with the improved skate thus becomes quite safe, since the speed may be readily checked at any moment.

The skate can be converted very quickly into a skate having only two rollers arranged in tandem fashion, in the longitudinal center of the skate. For this purpose, 5 the elastic holding sleeves α are slipped off laterally from the central portions of the axles K , K' , and then the nuts M , M' are turned so as to travel toward the center, until said nuts are clear of the arms J , J' . 10 The axles with the rollers thereon can then be removed through the open lower ends of the slots g . One of the rollers of each pair is then removed from its axle, and the other roller is shifted to the central portion of 15 the axle; the nuts M , M' are reversed, so that the washers N , N' will be on the inside of the arms J , J' , see Figs. 3 and 4. Of course, the dimensions of the rollers and of their fittings, and the distance between the 20 arms J or J' are so proportioned that the roller will fit properly between the arms J or J' when transferred to the central portion of the axle as described above. No parts need be placed on the axle exteriorly 25 of the nuts M or M' when the roller is placed in the center; still, for the sake of greater safety, the washers U , U' and the nuts V , V' may be placed on the axle ends in this case also. While the same axle K or K' may 30 be employed for carrying either one roller between the arms J or J' , or two rollers exteriorly of said arms, as described, an axle of exactly the same character, but of smaller length, may be substituted when the roller 35 is to be arranged centrally, as indicated in Fig. 3, with respect to the rear axle.

While I have not illustrated in the drawing a skate having only one central front roller and one central rear roller, this construction will be evident from Figs. 3 and 4, if we assume that we remove from these views, the roller shown between the front roller and the rear roller; that is to say, with only two rollers arranged in tandem 40 fashion, the central portion of the skate would look like that of Figs. 1 and 2, and the end portions like those of Figs. 3 and 4. It will be obvious that a three-roller arrangement might be obtained by employing 45 a pair of front rollers L or a pair of rear rollers L' (as in Figs. 1 and 2) in conjunction with a single rear roller L' or a single front roller L respectively (as in Figs. 3 and 4); these arrangements, while possible, 50 will probably never be used, and as, moreover, they will be readily understood, I have not shown them in the drawings.

By the addition of a supplemental roller 55 between the front axle K and the rear axle K' , I obtain either a skate having three rollers arranged in tandem fashion, as shown in Figs. 3 and 4, or a skate having five rollers, viz.: a pair of front rollers, a pair of rear rollers, and an intermediate central roller, as represented in Fig. 5. This sup-

plemental roller 20 is journaled in any suitable manner (generally with ball bearings) upon a supplemental axle 21 carried by a bracket or support 22 adapted to be secured detachably to the body of the skate. For 60 this purpose, the support 22 is provided with two bolts 23 and nuts 24 to correspond, said bolts being adapted to pass through the slots l and o of the rear plate B and of the front plate A respectively, so that the support 22 may be adjusted lengthwise of the skate, within certain limits, and then secured by tightening the nuts 24. The horizontal member extending across the top of the support 22 is in contact with the forward portion i of the rear plate B . The supplemental roller 20 is preferably of larger diameter than the rollers L and L' , and in any event it is so arranged that it will project downwardly beyond the plane passing through the bottom lines of the rollers L and L' , as shown in Fig. 4. Thus, when the supplemental roller is employed in conjunction with a single front roller and a single rear roller (Figs. 3 and 4), the three rollers cannot be on the ground at the same time if the ground is even, but only one of the end rollers can rest on the ground at the same time as the intermediate roller 20. The skater can also lift both end rollers off the ground after he has attained a certain speed, and thus run exclusively on the supplemental roller 20. Friction is thus reduced materially, particularly if the said roller is of a relatively large diameter, and a very 80 high speed may be attained. A similar effect 85 may be obtained with five rollers (Fig. 5), in which case the skater will start off with three rollers (the supplemental roller and either the front pair L or the rear pair L') resting on the ground, and after acquiring a certain speed, he can balance himself exclusively on the supplemental roller 20. A particularly skilful skater might even remove both front rollers and both rear rollers 90 so as to travel on the supplemental roller as the single roller of the skate.

Various modifications may be made without departing from the nature of my invention as set forth in the appended claims. 105

I claim as my invention:

1. A roller skate having front and rear rollers and an intermediate roller adjustable lengthwise of the skate. 110
2. A roller skate having front and rear rollers and an intermediate roller and provided with means for adjusting the distance of said intermediate roller from said front and rear rollers. 120
3. A roller skate having front and rear rollers, means whereby the distance between the front and rear rollers may be adjusted, and an intermediate roller adjustable toward and from said front and rear rollers. 125
4. A roller skate comprising a frame, 130

front and rear rollers whose axes are movable up and down relatively to said frame, and an intermediate roller whose axis is at a constant distance from the bottom of the frame the lower edge of the intermediate roller extending beyond the plane which passes through the bottom lines of the other rollers.

5. A roller skate comprising a frame, yielding rear and front carriers movable up and down relatively to said frame, an intermediate carrier held against vertical movement relatively to the frame, and rollers mounted on said carriers the intermediate 10 roller having its lower edge extending beyond the plane which passes through the bottom lines of the other rollers.

15. A roller skate comprising a frame, a

carrier movable up and down relatively to said frame, a roller mounted on said carrier, 20 and a lever for locking or releasing said carrier relatively to the frame.

7. A roller skate comprising a frame, a carrier movable up and down relatively to said frame, a roller mounted on said carrier, 25 a brake arranged to be applied by the movement of the carrier relatively to the frame, and means for locking the carrier to the frame.

In testimony whereof, I have signed this 30 specification in the presence of the subscribing witnesses.

JAMES E. WEAVER.
